UNITED STATES PATENT OFFICE.

ALBERT L. JOHNSON, OF ST. LOUIS, MISSOURI.

CORRUGATED BAR.

No. 858,517.

Specification of Letters Patent.

Patented July 2, 1907.

Application filed November 27, 1905. Serial No. 288,337.

To all whom it may concern:

Be it known that I, ALBERT L. JOHNSON, a citizen of the United States, and a resident of the city of St. Louis and State of Missouri, have invented a new and useful 5 Improvement in Corrugated Bars, of which the following is a specification.

My invention relates to corrugated bars for reinforced concrete constructions and particularly to that class of bars whose cross-sectional area is substantially uniform 10 throughout their length. It has for its principal objects to produce a new form of corrugated bar having a uniform cross-section; to produce a corrugated bar having projections or depressions arranged at such an angle to the axis of the bar that in any transverse plane 15 area of the section through the projections or depressions will be equal to the area of such section in any other transverse plane; to produce a corrugated bar having projections or depressions inclined to the axis of the bar and so disposed relatively to each other as to 20 neutralize the forces tending to move the bar laterally; to overcome the objectionable results arising from ribs, 25 projections or depressions inclined at an angle to the axis of the bar; and other objects hereinafter more fully appearing.

In the accompanying drawings forming a part of this specification and wherein like symbols refer to like parts wherever they occur, Figure 1 is a perspective view of the preferred form of bar; Fig. 2 is a view looking down upon the two faces made by the same roll; 30 Fig. 3 is a view of one face of the preferred form of square bar; Fig. 4 is a view looking at the edge of the bar formed at the meeting line of the rolls; Fig. 5 is a cross-section through the bar on the line 5—5 of Figs. 2 and 4, Fig. 6 is a cross section through the bar on the line 6—6 of 35 Figs. 2 and 4; Fig. 7 is a plan view of a flat bar having indentations in its opposite faces and embodying the invention; Fig. 8 is a longitudinal section on the line 8—8 of Fig. 7; and, Fig. 9 is a transverse section on the line 9—9 of Fig. 7.

In reinforced concrete construction it is desired to secure such a bond between the iron or steel bars and the concrete in which they are embedded that there shall be absolutely no relative movement. The tension bars are usually so located in the concrete that they extend 40 in the direction of the tensile stresses. Therefore, the desired bond is secured by providing the bars with alternate ribs and depressions transverse to the length of the bars. In the design of such bars the ribs were formerly permitted to fall at random on the several 45 faces of the bars and, hence, there might be transverse sections which would pass through the depressions or spaces between ribs on all the faces of the bar. Other sections might pass through ribs on all the faces of the bar. But the bar could only be as strong as its weakest 50 section. Therefore, the section in the plane passing through the depressions on all the faces of the bar, that

is, the net section of the bar, must be sufficiently large to give the bar the required strength. Obviously the larger sections passing through one or more ribs have a larger area than is required and, from the standpoint of 60 design for strength, the metal in ribs provided to secure the bond is wasted. In my application filed February 19, 1904, Ser. No. 194,362, I have described and claimed a corrugated bar of uniform cross-section in which this waste is obviated. The bar there described has pairs 65 of rows of alternate projections and spaces, the projections being at right angles to the axis of the bar and the projections and spaces of one row of each pair of rows is staggered with respect to the projections and spaces of the other row of the same pair of rows, whereby, any 70 transverse plane will intersect as many projections or ribs as spaces between the projections or ribs. Thus the cross-section of the bar is uniform and the metal in the ribs or projections contributes to the strength of the bar. By the bar herewith disclosed, the same uniformity of cross-section is secured by the use of sloping 75 or inclined ribs or projections or depressions, their arrangement being such that the ribs of each face compensate for the depressions in the same face.

The preferred form of bar has four faces and each face 80 is provided with a row of alternate ribs or projections 1 and depressions or spaces 2 between projections. The ribs are parallel to each other and are inclined to the axis of the bar at such an angle that the centers of opposite ends of adjacent ribs are exactly opposite each 85 other; or in other words, similar points of opposite ends of adjacent ribs lie in a line or plane at right angles to the axis of the bar. Thus, a right section at any point will contain equal areas of the rib. It may pass through only one rib of a face (as the section 5—5 of Fig. 2) or it 90 may pass through two ribs of a face (as the section 6—6 of Fig. 2); but in either case the area of the cross-section contributed by the rib or ribs is the same. If the depth of the spaces between ribs or projections be considered as the same as the thickness of ribs, it may be 95 said that in any right section the area contributed by the rib or ribs of any face intersected is equal to the area of the space or spaces intersected. What is true of one face is true of all the faces of the bar. Hence, the area of right sections of the bar is uniform throughout 100 the length of the bar.

As stated above, the uniformity of the cross-sectional area of the bar is due to the fact that the sloping ribs and spaces on each face are arranged to reciprocally compensate for each other at all points. This method of compensation by inclining the ribs gives rise to various stresses tending to move the bar laterally, to turn the bar on its axis, and to split the concrete. To guard against these stresses, the ribs and depressions of one 105 face of the bar are arranged to incline in an opposite direction to those of the next adjacent face but the angles of inclination to the axial plane passing through the 110

edge are equal. Otherwise stated, every rib of one face of the bar is in the same plane with the rib opposite it on the next adjacent face, said plane being inclined equally to said surfaces and consequently being inclined to the axis of the bar. By this arrangement, the diagonal stresses on the ribs of one face due to a longitudinal stress tending to pocket the concrete in the angle between said ribs are balanced by the like stresses on the ribs of the adjacent face. As a longitudinal stress in the opposite direction would tend to split the concrete by a kind of wedge action, it is important to guard against it. For this purpose, the two remaining faces are considered as a pair, and their ribs arranged in parallel planes inclined to the axis of the bar as above described. The angle of inclination which the plane of the ribs of one pair of faces makes to the axis of the bar is equal to and opposite the angle made by the plane of the ribs of the other pair of faces; in fact, the two planes may coincide, if the diagonal half of the bar 20 formed by one roll of the rolling mill shall have its ribs register with those of the other half of the bar which is formed by the second roll. In consequence of the ribs of one diagonal half of the bar being inclined in a direction opposite the direction of inclination of the plane of the ribs of the other diagonal half of the bar, the wedging action which would tend to split the concrete at one portion of the bar is offset by the pocketing action at the opposite portion.

It is advisable to leave a fillet 3 at the ends of the depressions in order to prevent the splitting of the concrete. In the practical manufacture of a rectangular bar, the fillet is formed along the two diagonally opposite edges where the rolls meet; but the other two edges are preferably truncated on account of the difficulty of keeping the rolls clean in practice. In the various forms of flattened or elliptic bars (such as shown in Figs. 7, 8 and 9), however, the fillet is of greater importance.

What I claim as my invention and desire to secure by Letters Patent is:

1. A bar for reinforcing concrete having a series of substantially equal transversely-inclined depressions arranged parallel with each other at a distance apart equal to the width of a depression, said depressions being inclined at such an angle that the initial point of the shoulder of one depression shall be in substantially the same transverse plane as the final point of the corresponding shoulder of the next adjacent depression.
2. A bar for reinforcing concrete having in each of two opposite faces a series of substantially equal transversely-inclined depressions arranged parallel with each other at a distance apart equal to the width of a depression, said depressions being inclined at such an angle that the initial point of the shoulder of one depression shall be in substantially the same transverse plane as the final point of the corresponding shoulder of the next adjacent depression.
3. A bar for reinforcing concrete having in each of two adjacent faces a series of substantially equal transversely-inclined depressions arranged parallel with each other at a distance apart equal to the width of a depression, said depressions being inclined at such an angle that the initial point of the shoulder of one depression shall be in substantially the same transverse plane as the final point

of the corresponding shoulder of the next adjacent depression, the respective ribs of said adjacent faces being in substantially the same planes.

4. A bar for reinforcing concrete having a series of equal transversely-inclined depressions in each face arranged parallel with each other at a distance apart equal to the width of a depression, the depressions of each face being separated by ribs and being inclined at such an angle that the sectional area of the depressions in any plane perpendicular to the axis of the bar shall be substantially equal to the sectional area of the ribs of said face in the same plane.

5. A bar for reinforcing concrete having on each face a series of equal transversely-inclined ribs arranged parallel with each other at a distance apart equal to the width of a rib, the ribs of each face being inclined at such an angle that the sectional area of the ribs in each face in any plane perpendicular to the axis of the bar shall be substantially equal to the sectional area of the spaces in said face in the same plane, and the respective ribs of the adjacent faces being opposite each other and in the same plane.

6. A bar for reinforcing concrete having on each face a series of equal transversely-inclined ribs arranged parallel with each other at a distance apart equal to the width of the rib, the ribs of each face being inclined at such an angle that the sectional area of the ribs in each face in any plane perpendicular to the axis of the bar shall be substantially equal to the sectional area of the spaces in said face in the same plane, and the angle of inclination of the ribs of one face being equal to the angle of inclination of the ribs of the next adjacent face, but the ribs of said faces inclining in opposite directions.

7. A four-sided bar for reinforcing concrete having on each face a series of alternate ribs and spaces of equal width inclined to the axis of the bar, the angle of inclination being such that similar points in opposite ends of adjacent ribs of the same face shall be in a plane perpendicular to the axis of the bar, each pair of ribs of two adjacent faces being in substantially the same plane with each other, and each pair of ribs of the other two faces being also in substantially the same plane with each other, but the planes of said pairs of ribs being inclined to each other.

8. A four-sided bar for reinforcing concrete having on each face a series of alternate ribs and spaces of equal width inclined to the axis of the bar, the angle of inclination being such that similar points in opposite ends of adjacent ribs of the same face shall be in a plane perpendicular to the axis of the bar, each pair of ribs of two adjacent faces being in substantially the same plane with each other, and each pair of ribs of the other two faces being also in substantially the same plane with each other, but the planes of said pairs of ribs being inclined to each other, and said bar having fillets along the edges where one pair of two adjacent faces meet the other two faces.

9. A four-sided bar for reinforcing concrete having on each face a series of alternate ribs and spaces of equal width inclined to the axis of the bar, the angle of inclination being such that similar points in opposite ends of adjacent ribs of the same face shall be in a plane perpendicular to the axis of the bar, each pair of ribs of two adjacent faces being in substantially the same plane with each other, and each pair of ribs of the other two faces being also in substantially the same plane with each other, but the planes of said pairs of ribs being inclined to each other, and said bar having fillets along the edges where one pair of two adjacent faces meet the other two faces, the edges where the two adjacent faces of each pair meet being truncated.
